UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

HOT TOP FOR MULTIPLE CASTING OF METAL INGOT.

Application filed February 3, 1923. Serial No. 616,721.

To all whom it may concern:

Be it known that BLOOMFIELD H. HOWARD and ERNEST J. TURNER, citizens of the United States, residing, respectively, at city of Washington, District of Columbia, and Pittsburgh, county of Allegheny, State of Pennsylvania, have invented certain new and useful Improvements in Hot Tops for Multiple Casting of Metal Ingots, of which the following is a specification.

Our invention relates to improvements in feeders for multiple casting of metal ingots.

The object of our invention is to provide a feeder adapted for multiple casting of metal ingots, supported within the upper end of the mold and so constructed that the molten metal may run out of the same after the metal has reached a predetermined height, into the adjoining mold and at the same time providing a feeder adapted to be used on any of the well known forms of molds without any change in the mold.

Another object of our invention is to provide a feeder having all of the advantages of the ordinary feeder used on molds in single casting, to prevent seams and holes known as "piping" and also reduces segregation to a minimum.

A further object of our invention is to provide a feeder having the necessary strength to support the trough for conveying the molten metal from one mold to the adjacent mold, when the molten metal has reached the predetermined level in the feeder and at the same time providing means whereby the trough is securely supported by the feeder and held against lateral movement and also providing means whereby a tight joint can be made between the feeder and the trough.

A still further object of our invention is to provide a feeder in which the metal in flowing from one mold to the adjoining mold, will not strike against the wall of the mold and injure the same and at the same time providing a simple cheap and effective feeder having certain details of structure and combination of parts herein-after more fully set forth.

In the accompanying drawings;

Figure 1 is a side elevation of a series of molds arranged in stepped relation and showing our improved feeder applied thereto with a trough in place between each mold

for conveying the molten metal from one mold to the other.

Figure 2 is a top plan view of a feeder showing the cut-out portion for supporting the trough and allowing the molten metal to overflow from the feeder to the adjoining mold.

Figure 3 is a side elevation of Figure 2.

Figure 4 is a top plan view similar to Figure 2 showing the supporting ribs terminating at a point below the lower end of the over-flow opening and serving as a support for the trough.

Figure 5 is a side elevation of Figure 4.

Figure 6 is an enlarged sectional view of the upper ends of two feeders in their operative position and showing in full lines the trough for conveying the molten metal from one mold to the adjoining mold.

Figure 7 is a top plan view of a modified form of feeder, in which three walls of the feeder are provided with the over-flow openings.

Figure 8 is a top plan view similar to Figure 7 showing all four walls having the over-flow openings.

Figure 9 is a sectional view of the upper end of an ingot mold showing a feeder in full lines therein and said feeder having the ribs omitted from the exterior and supported by a ledge on the inner wall of the mold.

Figure 10 is a sectional view similar to Figure 9 and taken at right angles thereto and showing a modified form of mold and feeder.

Figure 11 is a top plan view of a feeder partly broken away showing means for supporting the trough in the opening in the feeder.

Referring now to the drawings 1 represents a base which as shown in Figure 1 of the drawings is of a stepped form upon which the bases 2 of the several molds 3 are supported and whereby each succeeding mold has its upper end, lower than the other mold. Arranged within each mold is one of our improved feeders 4, which as shown is preferably of the form shown in Figure 2 of the drawings, having the ribs 5 extending from the upper edge and terminating at a point above the lower end as indicated at 6 and said ribs serving as supports for holding the feeder in the upper

end of the ingot mold and which is shown in our prior patents and therefore needs no further description. One wall of the feeder is provided with a cutout portion 7 at its upper end and which serves as an overflow opening to allow the molten metal to flow from the feeder to the feeder or mold succeeding it. As shown in Figure 1 of the drawings each mold has a feeder arranged therein and resting on the lower wall 8 of the opening 7 is a trough 9 which has its other end resting upon the upper end of the succeeding feeder as clearly shown in Figure 1 of the drawings. A tight joint is made between the trough and the walls of the opening 7 by means of clay or the like and whereby any leakage of the molten metal is prevented but any other means of making this joint tight could be employed without departing from our invention.

As will be seen from the drawings the opening 7 in the feeder, is at the upper end thereof and has its lower end 8 a considerable distance above the lower ends 6 of the ribs 5 whereby a sufficient amount of the feeder is in the mold and above the mold to retain the necessary amount of heat to prevent piping and practically eliminate segregation.

In some instances it might be necessary to relieve the feeder of the weight of the trough and the molten metal flowing therethrough and in which event we have provided the bridge 9' which has a short leg 10' resting on the upper edge of one of the molds and the long leg 11' resting on the upper edge of the adjoining mold and upon which the trough 9 is supported.

In the form shown in Figures 4 and 5 the two ribs 10 and 11 carried by the outer face of the feeder have their upper ends cut off at the point 12 and 13, which as shown in Figure 5 of the drawings is a short distance below the lower end 8 of the opening 7 and in which event the ribs serve as supports for one end of the trough as clearly shown in Figure 6 of the drawings.

In the modification shown in Figure 7 of the drawings three walls of the feeder are provided with the overflow openings 14, 15 and 16 whereby the several molds do not have to be arranged in a single line but can be arranged around a central mold and the metal poured into the same and the said metal flowing therefrom to the several molds arranged around the same. In Figure 8 of the drawings all four sides of the feeder are provided with the openings 17, 18, 19 and 20 in which event the central mold is adapted to supply molten metal to four molds arranged around the same.

In Figure 9 we have shown a feeder 21 in which the outer periphery is made perfectly plain without the ribs and of a size to fit within the enlarged upper bore 22 of

the mold 23 and resting on the ledge 24 formed by said enlarged bore and the feeder is provided with an opening 25 to receive the trough and allow the molten metal to pass therefrom, the same as in the other forms. In Figure 10 the whole feeder is within the upper end of the mold and supported by the same as shown in Figure 9 and is provided with an overflow opening 26 and the mold 27 is provided with an opening 28 corresponding therewith.

In Figure 11 of the drawings the overflow opening 29 on all sides is provided with a recess 30 to receive the end of the trough and whereby a tight joint may be formed between the feeder and the trough and which brings the upper face of the bottom of the trough flush with the bottom of the overflow opening.

As will be seen the feeder extends some distance into the mold and the molten metal as it flows through the trough and empties into mold will strike the wall of the feeder below the opening 7 and thus prevent any injury to the walls of the mold.

Having thus fully described our invention what we claim and desire to secure by Letters Patent is;

1. A hot top for ingot molds comprising a body portion having a discharge opening below the upper end. 95
2. A hot top for ingot molds comprising a body of refractory material and having a discharge opening adjacent its upper end. 100
3. A hot top for ingot molds comprising a body portion of refractory material having a discharge opening above its lower end. 105
4. A hot top for ingot molds comprising a body portion of refractory material and having a discharge opening adjacent its upper end, above the upper end of the mold. 110
5. A hot top for ingot molds for multiple casting of metal ingots, comprising a body portion of refractory material adapted to be supported within the upper end of the mold and extending above the same and having a discharge opening adjacent its upper end above the upper end of the mold. 115
6. A hot top for multiple casting of metal ingots comprising a body portion adapted to be supported on the upper end of the mold and having a discharge opening above the upper end of the mold. 120
7. A hot top for multiple casting of metal ingots, comprising a body portion adapted to be supported within the upper end of the mold and extending above the same and said body portion having a discharge opening adjacent its upper end considerably removed from the upper end of the mold. 125
8. A hot top for ingot molds, comprising a body portion having supporting means above the lower end to support the feeder on the upper end of the mold and having a discharge opening adjacent the upper end and 130

said supporting means serving as a support for a trough for conveying the molten metal from the feeder.

9. A hot top for multiple casting of metal ingots, comprising a body portion having a considerable portion extending into the mold and having an enlarged opening in one side above the upper end of the mold and arranged to receive and support a trough for conveying the molten metal from the feeder.

10. A hot top for multiple casting of metal ingots comprising a body portion of refractory material adapted to be supported within the mold and having a cut out portion below the upper end of the mold to function with a cut out portion in the upper end of the ingot mold.

11. A hot top for multiple casting of metal ingots, comprising a body portion of

refractory material adapted to be supported within the mold and having a cut out portion below the top of the mold the feeder being flush with the top of the mold having a cut out portion to function with the cut out portion of the feeder.

12. A hot top for multiple casting of metal ingots, comprising a body portion of refractory material adapted to be supported within the mold and extending above the mold and having a cut out portion below the upper end of the feeder and extending below the upper end of the ingot mold, said ingot mold having a cut out portion to function with cut out portion of feeder.

In testimony whereof we affix our signatures.

BLOOMFIELD H. HOWARD.
ERNEST J. TURNER.
